UNITED STATES PATENT OFFICE.

MAX BECK AND ROBERT O. ZIMMERMANN, OF NEW YORK, N. Y.

DESIGN FOR A MENU-COVER.

SPECIFICATION forming part of Design No. 32,313, dated March 6, 1900.

Application filed February 10, 1900. Serial No. 4,827. Term of patent 3½ years.

To all whom it may concern:

Be it known that we, MAX BECK and ROBERT O. ZIMMERMANN, citizens of the United States, and residents of the city of New York, borough of Manhattan, in the county and State of New York, have invented and produced a new and original Design for a Menu-Cover, of which the following is a full, clear, and exact description.

Reference is to be had to the accompanying drawing, forming a part of this specification, in which the figure is a perspective view of a menu-cover, showing our new design.

The leading feature of our design for a menu-cover consists in a rectangular panel having a metallic-like surface, surrounding which is a narrow border having a stippled appearance, the panel being raised or in relief with rela-

tion to the border, and the edges of the panel are indented in wave-like form. Displayed 20 within the panel are waved lines, forming a rectangular figure, at the corners and centers of which rounded projections appear.

Having thus described our invention, we claim as new and desire to secure by Letters 25 Patent—

The design for a menu-cover as herein shown and described.

In testimony whereof we have signed our names to this specification in the presence of 30 two subscribing witnesses.

MAX BECK.

ROB. O. ZIMMERMANN.
